UNITED STATES PATENT OFFICE.

WILLIAM A. GEIGER, OF CHICAGO, ILLINOIS, ASSIGNOR TO WILLIAM H. MINER, OF CHAZY, NEW YORK.

MEANS FOR SUPPORTING FACE-PLATES IN RAILWAY-CARS.

1,123,271.

Specification of Letters Patent.

Patented Jan. 5, 1915.

Application filed May 12, 1914. Serial No. 838,048.

To all whom it may concern:

Be it known that I, WILLIAM A. GEIGER, a citizen of the United States, residing at Chicago, in the county of Cook and State of Illinois, have invented a certain new and useful Improvement in Means for Supporting Face-Plates in Railway-Cars, of which the following is a full, clear, concise, and exact description, reference being had to the accompanying drawings, forming a part of this specification.

My invention relates to improvements in means for supporting face plates in railway cars.

The object of my invention is, to provide a support for face plates that will allow a limited vertical and a limited longitudinal movement of the buffer stems connected to the face plate, and at the same time will relieve the buffer stems of considerable weight and prevent undue wear of said stems.

In the drawings forming a part of this specification, Figure 1 is an end view of the body of a railroad car showing the means for supporting face plates embodying my invention in position thereon. Fig. 2 is a partial cross section on line 2—2 of Fig. 1. Fig. 3 is a partial vertical longitudinal section on line 3—3 of Fig. 1. Fig. 4 is an enlarged detail showing in longitudinal section one of the spring cases.

Referring to the drawings, the numeral 5 indicates a car body of the variety provided at the ends with a vestibule 6 having an end vestibule opening 7. The upper deck of the car roof is indicated at the numeral 8, the lower deck 9, and the hood at the numeral 10. The end opening of the vestibule is surrounded by the diaphragm face plate 11, the one shown being of the usual type having the vertical side members 12—12 and the upper transverse connecting member 13. The transverse face plate 14 is secured at its end 15—15 to the lower ends of the diaphragm face plate. Rearwardly the face plate 14 is engaged by the main buffer stem 16 and the side buffer stems 17—17 in the usual manner. The diaphragm face plate is provided at its upper end with the rearwardly extending piston rods 18—18 entering the vestibule of the car. Brackets 19—19 are secured to the car body, preferably near the upper portion of the diaphragm face plate, and to

the diaphragm face plate are secured, preferably near the lower end thereof, the brackets 20—20. Connecting rods 21—21, preferably two in number, are extended one between each upper bracket 19 and the lower bracket 20 on the same side of the diaphragm face plate, each of said rods being pivotally connected to the upper bracket 19 by suitable means, preferably the bolt 22 passing through the jaw 23 of the bracket arm 24 and through a suitable perforation in the end of the rod 21. The rod 21 is in two sections. The upper section 25 is threaded at its lower end to receive the stop nut 26 which engages against the upper end of a screw cap 27 threaded upon the section 25 of the rod, and also threaded upon a spring case 28 which is adapted to receive the plunger 29 with which the lower section 30 of the rod 21 is provided. The upper end of the section 30 of the rod 21 passes through the perforation 31 in the lower end of the spring case. A spring 32 is seated between the shoulder 33 with which the spring case 28 is internally provided at its lower end, and the head of the plunger 29. A further spring 34 is seated at its upper end against the cap of the spring case, and at its lower end against the head of the plunger 29. The springs in the spring cases 28 with which each rod 21 is provided are of sufficient strength to prevent extreme vertical movement of the diaphragm face plate, and consequent extreme vertical movement of the buffer stems, and allow sufficient yielding to prevent excessive rattling of the parts connected to the diaphragm face plate, either directly or indirectly, when the cars are in motion.

I claim:

1. In a railroad car, in combination, a car body, face plates at the ends thereof, and means for supporting the face plates comprising rods, each being secured at one end to the car body and at the other end to the face plate, each rod being in a plurality of sections, the said sections being connected by means of a spring case secured to one section, and slidably connected to the adjacent section, said spring case being provided with springs seated between the spring case and the rods.

2. In a connecting rod for connecting the car body to face plates for supporting the same, an upper section and a lower section,

a spring case and springs, one of the sections of the rod bearing the spring case, the other section of the rod slidably engaging the spring case, the latter section having a head, one of the springs being seated between said head and one end of the spring case, the other spring being seated between said head and the other end of the spring case.

10 3. In a rod for supporting face plates in railroad cars, an upper and a lower sec-

tion, springs, a spring case therefor connected to one of the sections and slidably engaged by the other section, the last mentioned section being provided with a spring seat, the springs being mounted between said seat and the ends of the spring case.

WILLIAM A. GEIGER.
